UNITED STATES PATENT OFFICE

108,559

DESIGN FOR A REFRIGERATOR

Alfred O. Boyce and George F. Appleby, St. Paul,
Minn.

Application November 6, 1937, Serial No. 72,670

Term of patent 14 years

To all whom it may concern:

Be it known that we, Alfred O. Boyce and George F. Appleby, citizens of the United States, residing in the city of St. Paul, county of Ramsey, and State of Minnesota, have invented a new, original, and ornamental Design for a Refrigerator, of which the following is a specification, reference being had to the accompanying drawings, forming a part thereof.

In the drawings Figure 1 is a perspective view showing our new design for a refrigerator, with the doors shown in open position; Figure 2 is a

front elevation of the same with the doors in closed position, and Figure 3 is a horizontal section taken on the line 3—3 of Figure 2.

The dominant feature of the design consists of the cylindrical front, doors and food compartment and circular shelves, as shown.

We claim:

The ornamental design for a refrigerator as shown and described.

ALFRED O. BOYCE.
GEORGE F. APPLEBY.
